UNITED STATES PATENT OFFICE.

JESSE A. BLOCH, OF WHEELING, WEST VIRGINIA.

DISPLAY BOX.

1,416,598.

Specification of Letters Patent. Patented May 16, 1922.

Application filed April 26, 1921. Serial No. 464,630.

To all whom it may concern:

Be it known that I, JESSE A. BLOCH, of Wheeling, in the county of Ohio and State of West Virginia, have invented certain new and useful Improvements in Display Boxes; and I do hereby declare the following to be a full, clear, and exact description of the invention, such as will enable others skilled in the art to which it appertains to make and use the same.

My invention relates to cartons and other types of containers having an element which forms part of the container when packed and which may be turned into an open position to exhibit advertising and other display matter related to the contained merchandise.

This general idea has heretofore been embodied in advertising schemes but they have had practical defects. In some instances the part which bears the display matter has not been an integral part of the receptacle or cover and hence it must be packed with care. In other cases this element has been formed by the merchant who buys and shows the commodity. He is supposed to cut the display card on prescribed lines so as to create a support for the card. The cutting of paste-board, to be successfully done, must be performed with care and precision. Careless operation tends to destruction. Consequently such display devices are either mutilated or neglected to an extent that impairs their commercial value.

My invention requires no part separate from the box and its cover and requires no cutting or fitting by the user.

Figure 1 shows an ordinary container and cover in perspective, the dotted lines indicating the flaps on the cover. Figure 2 shows the cover opened and having the flaps in alignment with the top of the cover and illustrating the function of the flaps, which previously held the cover, of co-acting with the display matter on the inner face of the cover to present the desired visual effect.

The receptacle 1 is of any desired material, form and construction. It is primarily designed as a container for packages of cigarettes. The cover 2, in its primary functional aspect, is a piece of material stamped out to form a top 3, side flaps 4, 5, and end flaps 6,

7. In the form illustrated these flaps are of a familiar design.

The inner face of the top of the cover bears advertising display matter; also the side flaps 4, 5. Near each end edge this top face bears a partial legend or figure, in the present instance a half of a bull's-eye consisting of a semicircle with concentric lines 8, 9, 10, and a central sphere 12 and an arrow 13 pointing into the sphere. The end flaps 6, 7, bear the partial representations adapted to co-act with those just described to complete the bull's-eye.

When the receptacle 1 is filled with the merchandise the cover is placed on it, the side and end flaps being received by the receptacle between its walls and the contained merchandise. The width of flap 5 is equal to the depth of receptacle 1 and that of flap 6 substantially so. Thus when the receptacle, the merchandise and the cover are assembled the top of the cover is about flush with the upper free edges of the receptacles.

The retailer receiving the package opens the cover by regarding flap 4 as the free edge and flap 5 as the hinged edge, that is, the cover is turned into open position, at right angles to the bottom of the container, on the line between its top and side flap 5. This flap 5 may remain in the receptacle between the side wall thereof and the packages of cigarettes. The side flap 4 and the end flaps 6, 7, are then turned into the plane of the top of the cover. This completes the display and, in the form illustrated, the visual effect is heightened by the bull's-eyes projecting beyond each end of the combined cover and display element.

I claim as my invention:

1. A merchandise container comprising a receptacle, a cover having side and end flaps adapted to be received by the receptacle between the walls thereof and the contained merchandise, display matter on the inner face of the top of said cover and on the inner faces of said flaps, said cover adapted to be turned into open position on the line between its top and one side flap, and the other side and end flaps adapted to be turned into the plane of the top of the cover and complete the display matter thereon.

2. A merchandise container comprising a receptacle, a cover having side and end flaps adapted to be received by the receptacle between the walls thereof and the contained merchandise, said end flaps being semicircular, display matter on the inner face of the top of said cover and on the inner faces of said end flaps and of semicircular design,

said cover adapted to be turned into open position on the line between its top and one side flap, and said end flaps adapted to be turned into the plane of the top of the cover and complete the display matter thereon.

In testimony whereof I have signed this specification.

JESSE A. BLOCH.
